UNITED STATES PATENT OFFICE.

JESSE W. RENO, OF LEADVILLE, COLORADO.

ROPE TRAMWAY.

SPECIFICATION forming part of Letters Patent No. 394,724, dated December 18, 1888.

Application filed June 25, 1888. Serial No. 278,093. (To model.)

To all whom it may concern:

Be it known that I, JESSE W. RENO, a citizen of the United States, residing at Leadville, in the county of Lake and State of Colorado, have invented new and useful Improvements in Rope Tramways, of which the following is a specification.

My invention relates to elevated tramways of the class in which the track is formed by ropes supported upon pillars or supports, and to inclined tramways of the class usually termed "gravity-roads," in which the weight of a descending loaded car will serve to draw an empty car up to the upper terminus; and it consists in the improved construction and combination of parts hereinafter fully disclosed in the description, drawings, and claims.

The objects of my invention are, first, to provide an inexpensive (comparatively) rope tramway which may be employed in inaccessible and rugged countries for the cheap and easy transportation of ore or other material from a mine on a mountain side to a mill, railroad, or roadway, or between similar points; second, to provide a one-track tramway with a switch at its middle in the length which will admit of one car descending and another car ascending over the same track and at the same time; third, to provide an obliquely-arranged pulley at the upper terminus of a gravity-tramway and to secure the tail-rope or traction-rope to the cars in such a manner that they will pass true to said pulley without danger of slipping off from the same; fourth, to provide such an oblique pulley with a brake for governing the ascent and descent of the cars upon the tramway and for stopping them when desired; fifth, to provide guide-rollers for such a tail or traction rope; sixth, to provide improved supports for the track-ropes of such a tramway; seventh, to provide an improved clamp for securing the track-ropes to the ends of the supports; eighth, to provide a solid track or support for the cars at the lower or dumping terminus.

The cars are suspended from the axles of the wheels and are provided with hinged bottoms, which are automatically opened by means provided at the dumping-platform and which are automatically closed after the load is dumped.

An important feature of my invention is the provision by which the upper portions of the rope-supports are free to have a movement 55 with and in the line of the track-ropes under the weight of the moving cars in causing the ropes to bend between the supports, in the provision whereby two cars are allowed to pass each other at the same time upon a single-track tramway composed of two track-ropes 60 secured upon suitable supports, and in the provision of suitable platforms at the loading and unloading ends of the track.

In the accompanying drawings, which form 65 a part of this specification, and in which the same reference-numerals indicate the same parts, Figure 1 represents a side elevation of my improved tramway, showing the hill or mountain upon which said tramway is constructed in sectional profile; Fig. 2, a side elevation of the upper end of the tramway and the loading-platform; Fig. 3, a top plan view of the same; Fig. 4, a section of the grooved tread part of the oblique pulley at the upper end of the tramway; Fig. 5, a side view 70 of one of the rope-supports; Fig. 6, a transverse vertical section of the tramway, showing the rope supports in elevation; Fig. 7, a top plan view of one of the ties or sleepers for 75 said rope-supports; Fig. 8, an enlarged detail view of the rope-clamp at the end of a support; Fig. 9, a side elevation of the switch; Fig. 10, Sheet 1, a top plan view of the same; Fig. 11, Sheet 4, a transverse vertical section 80 on the lines *x x* of Figs. 9 and 10; Fig. 12, a sectional detail view of the cap of one of the rope-supports at the ends of said switch, showing the manner of anchoring the ropes and the switch-rods; Fig. 13, a detail view of said 85 cap, showing the anchor-seats for the switch-rods; Fig. 14, a longitudinal vertical section 90 of the dumping terminus of the tramway; Fig. 15, a transverse vertical section of the dumping terminus and a car upon the same. Fig. 15^a is a detail section of the latch-bar 95 for the car-door; Fig. 16, a detail bottom plan view of the releasing device for opening the bottom or dumping door of the car; Fig. 17, Sheet 1, a section of a wheel of one of the 100 cars; Fig. 18, an axial sectional detail view of the rim of said wheel, showing the rubber lining as it appears after it is secured in place in the groove of the rim; and Fig. 19 is a detail

showing the wire tie for the ends of the rubber lining.

In the drawings, the numerals 1 indicate the two track-ropes, which are preferably strong wire ropes, each of one-half the length of the track. The upper ends of said track-ropes are secured by means of suitable anchors, 2, and are supported at a distance from said anchors upon the upper ends of two outwardly-inclined supports or posts, 3, which rest with their lower ends upon a tie or base, 4, and are connected by a cross-piece, 5, near their upper ends. The portions of the track-ropes between said supports and said anchors are horizontal and in a plane with the loading-platform 6, which is formed by horizontal beams 7, supported at their inner ends near said anchors and near their outer ends by upright supports or posts 8, which rest upon said tie or base 4. The upper ends of said upright posts 8 support two inclined beams, 9, the inner ends of which are secured to the inner ends of the platform-supporting beams 7, and the outer ends of which are connected by a cross-piece, 10. The shaft 11 of a grooved pulley, 12, is journaled at an angle to said inclined beams 9 in boxes 13, secured upon the same in such manner that said pulley will be at an angle to the edges of said inclined beams and to their plane, for a purpose hereinafter described. Said pulley is formed with a wide and flat rim or periphery, 14, Fig. 4, which has a deep groove, 15, in its middle, preferably lined with a rubber or similar yielding packing, 16, and a brake-lever, 17, is fulcrumed upon an upright, 18, and has a weight, 19, or a spring for forcing the brake-shoe 20 of said lever from above against the flat rim of said pulley.

The track-ropes are supported at suitable distances apart by supports or posts 21, formed with rounded lower ends, 22, Fig. 5, which fit and may rock in cylindro-concave chairs or pillow-blocks 23 upon the upper faces of the ties or sleepers 24, which rest upon the side of the mountain. Said supports are united near the upper ends by cross-pieces 25, and two anti-friction or supporting rollers, 26, for the tail-rope or traction-rope are transversely journalled between said supports. The upper ends of said supports are provided with clamps or caps composed of two pieces or jaws, 27, clamped upon the ends of said supports by nutted bolts 28 and formed with upwardly-projecting lips 29, between the concave sides of which said track-ropes are clamped, as plainly shown in Figs. 6 and 8 of the drawings.

At the middle of the track is formed a switch, 30, for the purpose of allowing one car to pass over the other as they meet in ascending and descending. Said switch is composed of two sets of track-rods, 31 and 32, which, respectively, are supported one set above the other. The supports or posts immediately above said switch are provided with caps 33, formed with grooved ridges 34 and

35, Fig. 13, upon their upper faces, and the ends of the upper set of track-rods, 31, are inserted through the outer ridges, 34, and secured upon the under sides of said caps 33 by nuts 36, and the ends of the lower set of track-rods, 32, and of the track-ropes are inserted through the inner ridges, 35, and secured upon the under sides of said caps 33 by nuts 37 and 38, Fig. 12, said lower track-rods and track-ropes forming one continuous track, while the upper track-rods form a track of a somewhat broader gage. Said upper and lower sets of track-rods are inserted in the same manner at 80 the lower end of the switch to ridged caps 39, secured upon the upper ends of short posts 40, which are connected by cross-pieces 41 and supported by said track-rods and by the lower lengths of track-rope, which are secured 85 in said caps in the same manner as the ends of the upper lengths. The upper track-rods are formed with upwardly-inclined portions, straight portions, and downwardly-inclined portions, and the lower track-rods with downwardly-inclined straight portions and upwardly-inclined portions, and for the purpose of spacing said track-rods and supporting them at their proper distances and in their proper shape two U-shaped frames or supports, 42, 90 are provided, which have the upper track-rods supported in their upper ends at the ends of said straight portions, and the lower track-rods held drawn down by bolts 43, which pass through ears 44 at the ends of said straight 100 portions of said lower track-rods, as plainly shown in Fig. 11.

At the dumping terminus of the track the track-ropes are carried over the upper faces of two beams, 45, which are supported upon posts 46, and are thereupon secured by anchors 47. Said beams 45 are faced with angle irons or rails 48, upon which the track-ropes may rest and the wheels of the cars run, said angle-irons having the upper ends, 49, inclined 105 for the purpose of allowing the grooved car-wheels to run up on said irons or rails and clear of the ropes.

The cars 50 are formed of rectangular sheet-iron boxes 51, which are supported by hangers 52 upon their upper sides from the axles 53 of the grooved wheels 54. The rims of the wheel of one car are formed with one peripheral groove, 55, which may fit upon the track-ropes and upon the lower track-rods of the 110 switch, and the rims of the wheels of the other car are formed with said inner peripheral grooves, 55, and with outer peripheral grooves, 56, which may fit upon the upper track-rods of the switch, which are secured at a broader 115 gage, so that when the cars meet at the switch the car having only one groove in its wheel will always pass on the lower switch-rails or track-rods and beneath the car having two grooves in its wheels, which will leave the inner track at the ridged caps upon the support and travel with the outer grooves of its wheels upon the upper switch-rails or track-rods above the other car until it again strikes 120 125 130

the track-ropes with the inner grooves of its wheels at the other end of the switch.

The grooves in the car-wheels are lined with rubber or similar material, which linings consist of a strip, 57, which is placed in said groove and has its ends united by means of pieces of wire, 58, inserted through said ends and through holes 59 in the flanges or sides of the groove and having their ends twisted together. A strip thus secured in the groove of the wheel will be forced into said groove and to correspond to its shape by the track-rope as the wheel travels upon the same.

Referring to Fig. 10, it will be seen that the branch ropes 60' at the ends of the tail-rope 60 are secured to the upper ends of the cars at their corners, and said branch ropes are attached to the end of the tail-rope for the car which passes over the upper switch-track rods, so as to bring the knot 60", which unites said branch ropes and tail-rope, to register with a point at a distance from the upper right-hand corner of said end of about one-fourth of the width of the car, and to the end of the tail-rope for the car which passes over the lower switch-track rods, so as to bring the rope-knot 60", which unites the branches of the rope for said car, to the other end of the tail-rope to register with a point at the same distance from the lower left-hand corner of said end, so that both ropes will be supported upon the centers of the rollers between the supports. This diminishes the tendency of the cars to move sidewise, since the rope is not attached at a point on the vertical line through the center of gravity of the car. It will also be seen that the short posts 40 are provided with a roller, 26, for the tail-rope the same as the upper post, 21.

Referring to the frames which support the switch, I prefer to make them of railroad-iron and weld their upper ends into seats, within which the upper switch-track rods are firmly secured.

Referring to the car, I prefer to secure it by angle-strap 52 to the square part of the axle and to mount the wheels so as to turn freely upon the axle. The car which passes over the lower switch-track rods is provided upon its top with rollers 61, near the ends of said top, for the support of the tail-rope during the first half of a descent and the last half of an ascent of said car, when said rope will travel over the top of said car. By securing the ends of the tail or traction rope to the cars in the aforescribed manner one pulley, secured obliquely and in the manner hereinbefore described at the upper end of the track, will only be required for said rope to pass over, as the rope will enter and leave the groove in the periphery of said pulley at a tangent and directly in line with the points of attachment of its ends.

The upper end of each car is formed with an outwardly-opening door, 62, Fig. 14, which is hinged at its lower edge upon the lower side of the angle-iron end frame, 63, of the car

and provided with a hooked latch, 64, at the upper edge, which latch engages the upper side of the angle-iron end frame. When the car is loaded at the upper end of the tramway, said door is tilted down against the platform, and the ore or material for the load of the car may be shoveled into the open end or dumped into it from a bin or receptacle through a chute.

The bottom 65 of the car is hinged at one side edge to the side of the car, and its free edge is engaged, when said bottom is closed, by a bar, 66, of angle-iron, which is hinged to the side of the car by means of upwardly and inwardly projecting hooks 67, which engage slots 68 in said side. Said angle-iron bar has one side projecting in under the lower edge of the side and supports the free edge of the hinged bottom upon said side. Flat springs 69 are secured to the sides of the car and bear with their lower ends against the outer side of said angle-iron bar 66, forcing said bar inward to engage and hold the free edge of said hinged bottom when the latter is closed. The horizontal side of said angle-iron bar 66, which I will term the "latch-bar," is provided at intervals upon its under side with beveled lugs 70, which will serve to admit of said hinged bottom being forced with its free edge against said lugs and forcing said latch-bar back against the springs, so that said hinged bottom may be slammed shut against the beveled lugs. Said latch-bar is formed with a laterally-projecting arm, 71, provided with a downwardly-projecting pin or bolt, 72, at its outer end, upon which pin or bolt a sleeve or roller, 73, is secured and may revolve. A flat bar or plate, 74, is pivoted upon the under side of one of the beams 45 at the dumping terminus, and said bar or plate is formed with an oblique upwardly-bent lip or flange, 75, at its outer end, said lip or flange having its inwardly-pointing end toward the lower end of the dump. The inner arm of said pivoted bar or plate 74 bears against a stop, 76, and has a coiled spring, 77, which draws said inner arm against said stop. It will be seen by reference to Figs. 14, 15, and 16 that when the car arrives at the dump the pin of the latch-bar will be engaged by the oblique flange 75, which will draw said latch-bar out and release the hinged bottom, while the spring will permit said pivoted plate or bar 74 to yield and to be tilted out of the way by said pin 72 when the car again ascends. A lever, 78, is fulcrumed under the beam 45 of the dump opposite said pivoted bar or plate, and said lever is provided with a bumper, 79, upon its inner end, with which it may bear against the hinged bottom of a car, and with a poise, 80, upon the outer end of the lever, which poise is of sufficient weight to counterbalance and close the hinged bottom of the car. A yielding bumper, 81, is preferably arranged to receive the descending poise of said lever.

In practice the car at the upper end of the tramway is filled through its open end, as de-

scribed, said car being held securely by the brake, which is applied to the oblique pulley. When the car is loaded, the brake is raised from said oblique pulley and the loaded car 5 will descend, pulling the empty car at the other end of the tail-rope or traction-rope up by said rope. The speed of the cars may be controlled by said brake and oblique pulley, and when the cars arrive near the switch the 10 speed is preferably decreased. One car will pass over the other at said switch, and the cars will continue in their respective directions until they are stopped by the empty car arriving at the upper terminus of the track 15 and the brake being applied to said oblique pulley. The loaded descending car will have its latch-bar disengaged by the oblique flange 75 drawing the pin 72 and said latch-bar out as said pin engages said flange, and the hinged 20 bottom of said car will swing down, dumping the load. The weight of the load upon said hinged bottom will raise the weighted end of the closing-lever 78, as indicated in dotted lines in Fig. 15, and the poise upon said lever will slam said hinged bottom shut when 25 the load is dumped.

The pile of ore at the dumping terminus will be comparatively long and low on account of the loads of the cars being dumped in their 30 entire lengths by the tilting bottoms, and the supports for the dumping terminus of the track will therefore not need to be as high as would be necessary if the loads were dumped in a short and high pile from a short trap in 35 the bottom of each car or from short cars.

If desired, several dumping mechanisms and unlocking and closing devices may be arranged at the lower terminals of the track and be placed into or out of operative position 40 at will.

It will be obvious from the foregoing description that this tramway may be put up and conducted upon mountain sides where no ordinary road or tramway could be made, so 45 that mines which could not profitably be worked on account of their inaccessibility may now be worked with profit by means of my tramway for carrying down the ore and for carrying up all implements and provisions 50 needed. All the parts which compose the tramway are of sufficient compactness to be carried by common mountain mules, so that the tramway may be laid in any locality which is accessible for a man and a mule or 55 horse.

By supporting the track-ropes upon the supports having the rounded ends 22, resting in the chairs or pillow-blocks 23, said supports may swing slightly and allow the track-rope 60 to yield slightly to the weight of the cars, and by having the switch supported by the supports at the upper end, while the track-ropes and rods are merely held spaced by the posts 40 and cross-pieces 41 at the lower end of said 65 switch, said switch will not be rigid on account of its track-rods and U-shaped frames, but will form a yielding part of the yielding and flexi-

ble track. Said power of yielding possessed by this track will prevent sudden jars and strains which might be caused by rapid descent of heavily-loaded cars, admitting of comparatively high speed with safety. 70

By having one track of the switch above the other only the same width of supports will be required over the entire length of the 75 tramway, and the desired flexibility for the tramway will not be obstructed and destroyed by a switch with two tracks alongside each other, which would require a very wide and solid support, besides interfering with the 80 alignment of the tail-ropes.

The switch at the middle of the track will admit of only one track being employed for moving two cars in opposite directions by the gravity of the loaded car, thus considerably 85 cheapening the cost of such a tramway, and the capacity, safety, and general effectiveness of said tramway are increased over wire-rope tramways having only one track-rope by reason of the track being formed by two 90 ropes.

Having thus fully described the construction and arrangement or combination of parts of my tramway, its operation, and advantages, what I claim as new is— 95

1. A rope tramway which consists of two track-ropes and pairs of supports for said ropes, each pair of supports being rigidly connected and movably supported at their lower ends, substantially as described. 100

2. The combination, with a rope tramway which consists of two track-ropes and pairs of supports for said ropes, each pair of supports being rigidly connected and movably supported at the lower ends, of cars having 105 grooved wheels which travel upon said track-ropes and their supports, substantially as described.

3. A tramway which consists of one track with a switch at its middle, in combination 110 with two cars and a tail-rope or traction-rope of the length of the entire track secured with its ends to said cars and passed around a pulley at the upper end of the track, substantially as described. 115

4. The combination of a tramway which consists of one track, a switch at the middle of said tramway and formed with one elevated and one depressed track one above the other, a pulley at the upper end of the track, two 120 cars, and a tail-rope or traction-rope of the length of the entire track secured with its ends to said cars and passed around said pulley, substantially as described.

5. The combination of an inclined rope 125 track, a switch at the middle of the same and formed with an elevated and a depressed track one above the other, a guide-pulley at the upper end of said rope track, two cars, a tail-rope or traction-rope secured at its end 130 to said cars and passed around said guide-pulley, and rollers upon the upper side of the car which travel on the depressed track of the switch, substantially as described.

6. The combination of a rope track, supports for said track rigidly connected in pairs and movably supported at the lower ends, a switch, two upper end supports for said switch 5 rigidly connected and movably supported at the lower ends, and two lower end supports for said switch rigidly connected and depending freely from the lower end of said switch and from the rope track, substantially as described.

7. The combination, with a track, a car having the peripheries of its wheels grooved to travel upon said track, and a car having the peripheries of its wheels formed with grooves 15 to travel upon said track and with grooves outside of said grooves, of a pair of depressed lower switch-rails which form continuations of said track, and a pair of raised upper switch-rails upon which said outer grooves of 20 said car-wheels may travel, substantially as and for the purpose described.

8. In combination with the track-ropes and the cars formed, respectively, with one set of peripheral grooves, 55, in the wheels and with 25 two sets of peripheral grooves, 55 and 56, in the wheels, the end supports, 21 and 40, the caps 33 and 39, formed with the inner and outer grooved ridges and having the ends of said track-ropes secured in the inner ridges, 30 the depressed lower track-rods having their ends secured in said inner ridges, the raised upper track-rods having their ends secured in said outer ridges, and the U-shaped supports for spacing said track-rods, substantially as 35 and for the purpose described.

9. The combination of a rope track, supports 21, rigidly connected to each other and movably supported at the lower ends, caps 33, formed with outer and inner grooved ridges, 40 34 and 35, and having the ends of the rope track secured in said inner ridges, the short posts 40, rigidly united and provided with caps 39, formed with outer and inner grooved ridges having the ends of the rope track secured in said inner ridges, the U-shaped frames 42, the upper raised track-rods secured with their ends in said outer ridges of said caps 33 and 39, supported upon the upper ends of said U-shaped frames, and the lower 45 50 depressed track-rods secured with their ends in said inner ridges of said caps 33 and 39 and formed with ears 44, secured to said U-shaped frames by bolts 43, substantially as described.

55 10. In combination with a rope track formed with a switch upon its middle and two cars traveling upon the same, a grooved pulley journaled to revolve in a plane at an angle to the direction and to the plane of said track,

60 and a tail-rope or traction-rope passed around said grooved pulley and having its ends secured, respectively, to the upper and lower edges of the ends of the cars and near opposite corners to bring the rope to reach and 65 leave said grooved pulley tangentially, substantially as described.

11. In an inclined rope tramway, the com-

bination of a platform supported by two horizontal beams, 7, outwardly-inclined supports 3 for said beams, and having a cross-piece, 5, 70 uprights 8, inclined beams 9, supported by said uprights and by said platform, a pulley formed with a wide flat rim having a lined groove, and having its shaft journaled in boxes upon said inclined beams 9 at an angle to said beams, a weighted brake bearing against the flat rim of said pulley, track-ropes anchored at the inner end of said platform-beams 7 and supported by the upper ends of said inclined supports 3, and formed with a switch 80 upon their middle, cars traveling upon said track-ropes, and a tail-rope or traction-rope passed around said grooved pulley and secured with its ends to the upper ends of said cars, respectively, to the upper and lower 85 edges of said ends and near opposite corners of the same, substantially as described.

12. In a rope gravity-tramway, the combination of sleepers having cylindro-concave chairs or pillow-blocks, pairs of track-supports or points having the lower ends rounded to fit and rock in said chairs and united by cross-pieces, track-ropes secured in the upper ends of said supports, and pairs of rollers journaled between said supports, substantially as described.

13. In a rope gravity-tramway, the combination of two track-ropes, pairs of supports for said ropes, a switch at the middle of said track-ropes, an oblique pulley at the upper 100 ends of said ropes, two cars traveling upon said track-ropes, a tail-rope or traction-rope passed around said oblique pulley and having its ends secured, respectively, to the upper and lower edges of the ends of said cars 105 and near opposite corners, and pairs of rollers journaled transversely between said supports for supporting the parts of said tail or traction rope as they travel in opposite directions, substantially as described.

14. In a rope tramway, the combination of the track-ropes, supports or posts for the same, and caps formed of two jaws clamped upon the ends of said supports by nutted bolts and formed with upwardly-projecting lips, 115 which clamp said ropes, substantially as described.

15. A gravity-tramway composed of two track-ropes supported upon posts, a suspended switch having two sets of tracks, one below 120 the other and of different gage, and two connected cars, one of which has wheels having grooves adapted to run upon the track-ropes and upon the switch-track of widest gage, substantially as described, for the purpose 125 specified.

16. In a gravity-tramway, the combination of two track-ropes and a suspended switch having rails of different gage arranged one above the other with two connected cars suspended from axles, the wheels of one of the cars being adapted to the track-ropes and to the broad-gage rails of the switch, and the wheels of the other car being adapted to the

track-ropes and to the narrow-gage rails of the switch, substantially as described.

17. A tramway composed of two track-ropes, rigidly-connected supports for each rope, and a switch-track of upper and lower rails suspended in line with the track-ropes for the passage of cars one above the other, substantially as described.

18. In a gravity-tramway, a car provided with a hinged bottom and a latch for the free edge of said bottom, and provided with a laterally-projecting arm which has a downwardly-projecting pin, in combination with a plate provided with an oblique and upturned flange secured to the dumping-platform for engaging said pin and drawing said latch, substantially as described.

19. In a tramway, a car-box having a hinged bottom, and a latch-bar for engaging the free edge of said bottom and provided with a laterally-extended arm which is formed with a downwardly-projecting pin which has a sleeve or roller, in combination with a plate or bar formed with an upturned oblique flange and pivoted to the dumping-platform to engage said pin with the outer end of said flange and draw the same outward, a stop for the inner end of said plate or bar, and a spring secured to said inner end of the plate or bar and to said stop, substantially as described.

20. In a tramway, the combination of the track, a car which has its wheels traveling upon said track and which is provided with a hinged bottom, and a latch for the free edge of said bottom and provided with a laterally-extending arm which is provided with a downwardly-projecting pin, in combination with a plate or bar which is pivoted beneath one track-rail and provided with an upturned oblique flange at its outer end, which flange points inward at the end pointing in the direction of the descent of said car, a stop for the inner end of said plate or bar, and a spring secured to said inner end and to said stop, substantially as and for the purpose described.

21. In a tramway, the combination of the track, a car having its wheels traveling upon said track and provided with a bottom hinged to one side of said car and provided with a latch, and a lever which is fulcrumed under one rail of said track and formed with a bumper upon its inner end for bearing against said hinged bottom, and with a poise upon its outer end for closing said bottom, substantially as described.

22. In a tramway, the combination of the track, a car which has its wheels traveling upon said track and provided with a bottom hinged to one side and provided with a suitable latch, a lever fulcrumed under said track and provided with a bumper upon its inner end for bearing against said bottom and with a poise upon its outer end for closing said bottom, and a bumper arranged beneath said bottom, substantially as described.

23. In a rope tramway, the combination of the rope track, a car having grooved wheels

which travel upon said track-ropes, beams or supports under said track-ropes at the dumping terminus, and angle-iron rails upon the upper sides of said beams, having the track-ropes resting upon them and formed with slightly-inclined upper ends, substantially as and for the purpose described.

24. In a rope tramway, the rope-supports mounted in chairs or pillow-blocks adapted to allow a vibratory movement to the upper ends of said supports in the line of the track, substantially as described, for the purpose specified.

25. In a rope tramway, the track-ropes, each anchored at its ends and supported at intervals by upright rigid cross-frames having a clamping device for each rope and having concave sockets confining supports at their lower ends, substantially as described, for the purpose specified.

26. In a rope tramway, the track-ropes, each anchored at its ends, in combination with upright rigid cross-supporting-frames having metal jaws adapted to be clamped and bound upon said ropes and conforming to the grooves of the car-wheels, substantially as described.

27. In a rope tramway, the track-ropes, in combination with rigid supporting cross-frames having jaw-irons for each track-rope, consisting of the jaws 27 27, formed with lips 29 29, having concave seats fitting and embracing the rope and fitting the grooves of the car-wheels, and the clamping-bolts 28 for said jaw-irons, substantially as described.

28. A single-track tramway consisting of the two track-ropes, cross-supports therefor, and a switch connected in the middle of their length having independent tracks one above the other, one having a broader gage than the other, whereby cars ascending and descending the single track are permitted to pass each other, substantially as described.

29. A single-track tramway consisting of two track-ropes, cross-supports therefor, and suitable clamping devices for said track-ropes, and a switch having independent tracks one above the other, one forming a continuation of said track-ropes and the other having a broader gage, substantially as described, for the purpose specified.

30. The combination of a single-track tramway consisting of two track-ropes and a switch having two independent tracks, one above the other, of different gage, with cars having wheels adapted to run upon said track-ropes and to pass each other over the switch, substantially as herein set forth.

31. In a single-rope-track tramway, a switch suspended by the two track-rope supports and having two tracks, one above the other, composed of rods and U-shaped frames to which said rods are firmly secured at different distances apart, one pair of said rigid switch-track rods forming a continuation of the two track-ropes, substantially as described.

32. A single-track-rope tramway consisting

of the rope tracks anchored at each end and a middle section composed of a rigid frame having two independent tracks of different gage one above the other and suspended from

5 rope tracks having movable supports, substantially as herein set forth.

33. A tramway composed of two track-ropes supported upon posts movably socketed in pillow-blocks, in combination with switch-
10 tracks and a frame supporting the latter between said posts, substantially as described.

34. A tramway composed of two track-ropes, rigidly-connected supports for each rope, and a switch having rigid tracks arranged in pairs
15 one above the other and connected to said supports, substantially as described, for the purpose specified.

35. In a rope tramway, the rope-supports rigidly connected in pairs, each support having a fixed connection with the ropes and a free connection with confining pillow-blocks or chairs, in combination with a switch suspended upon and between the said rope-supports, substantially as described.

25 36. A tramway composed of two track-ropes, rigidly-connected supports for each

rope, and a switch having tracks supported in line with and in planes above and below the said track-ropes, substantially as described, for the purpose specified.

30

37. In a gravity-tramway, the combination, with track-ropes anchored at each end and secured upon rigidly-connected but movable pairs of supports, of stationary platforms over and upon which the said track-ropes pass to their anchorage, substantially as herein set forth.

35

38. A tramway composed of two track-ropes anchored at their ends and secured upon the ends of posts rigidly connected cross-
40 wise in pairs and mounted in chairs or pillow-blocks adapted to allow said connected posts to have a movement with and in the line of the track-ropes under the weight of the cars, substantially as described.

45

In testimony whereof I have hereunto set my hand in the presence of two subscribing witnesses.

JESSE W. RENO.
